United States Patent Office

Des. 186,161
Patented Sept. 22, 1959

186,161

CADDY CART

George R. Chervenka, St. Louis, Mo., assignor to Shampaine Company, St. Louis, Mo., a corporation of Missouri

Application April 6, 1959, Serial No. 55,362

Term of patent 14 years

(Cl. D14—3)

FIG. 1

FIG. 2

Fig. 1 is a side elevational view of the caddy cart embodying my new design;

Fig. 2 is a top plan view thereof; and

Fig. 3 is an end elevational view thereof.

I claim:

The ornamental design for a caddy cart, substantially as shown.
